CLOTHESPIN

Espa S. Gardner, North Platte, Nebr.

Application February 8, 1934, Serial No. 710,358

3 Claims. (Cl. 24—137)

This invention relates to a clothespin and it aims to provide a more efficient and durable construction of composite form of rust-proof metal and wood.

- 5 It is particularly aimed to provide a construction in which metal will not contact with the clothes or articles engaged and a construction having a novel spring wire means to exert the desired pressure.
- 10 It is further aimed to provide novel interfitting wire and groove means between the spring and wooden jaws.

The more specific objects and advantages will become apparent from a consideration of the 15 description following taken in connection with the accompanying drawing illustrating an operative embodiment.

In said drawing:—

20 Figure 1 is a view of the clothespin in side elevation;

Figure 2 is a reverse side elevation to Figure 1; Figure 3 is an elevation taken at a right angle to Figure 1;

25 Figure 4 is an elevation reverse to Figure 3; Figure 5 is a cross sectional view taken on the line 5—5 of Figure 1; and

Figure 6 is a detail section taken on the line 6—6 of Figure 3.

Referring specifically to the drawing, the device 30 comprises two jaws 10 preferably made of a suitable hard wood having coacting flaring surfaces at 11 to aid in engaging the line and clothes or other articles to be fastened thereon.

A spring device is shown at 12 and may be 35 formed from a single strand of resilient wire, preferably a rustless metallic wire. This wire or spring has two complete coils as at 13 and the terminals are formed into arms 14. Such arms are elongated and disposed or countersunk in 40 grooves 15 provided in the adjacent surfaces of the jaws 10.

In order that the arms will have a better bearing against the jaws, they are non-straight as shown, having horizontal terminals as at 16 across which plates 17 are fastened, as by spurs 18, integral therewith and driven into the jaws.

45 In order to prevent spreading of the coils 13 and aid in positioning the parts and the resilient action of the spring device, an anchor member

is provided at 19 preferably in the form of a non-rusting metallic wire, the same being welded or otherwise rigidly fastened as at 20 to one of the coils, and the anchor 19 adjacent both ends being coiled into loops 21 tightly around both 5 coils 13, and clinched thereto.

In the use of the device, the clothes or other articles while on the line are engaged between the surfaces 11 and the pin pushed down thereover. Coils 13 are contractile and hence the 10 pin will automatically lock on the material and line. A compound grip on such material is produced by the coils and the material will not be dislodged by the action of a heavy wind nor will the same be injured by the use of the pin. 15

Various changes may be resorted to provided they fall within the spirit and scope of the invention.

I claim as my invention:—

1. A pin of the class described having a spring 20 device comprising a plurality of coils and arms extending from the terminals of the coils, anchor means preventing spreading of the coils, and coacting jaws fitted to said arms, said anchor means being formed of a length of wire having a loop at each end enclosing the coils at opposite sides of said arms, one of said loops being fixedly secured to one of the coils. 25

2. A pin of the class described having a spring 30 device comprising a plurality of coils and arms extending from the terminals of the coils, anchor means preventing spreading of the coils, and jaws having grooves in which said arms are fitted, said anchor means being formed of a 35 length of wire having a loop at each end enclosing the coils at opposite sides of said arms, one of said loops being fixedly secured to one of the coils.

3. A pin of the class described having a spring 40 device comprising a plurality of coils and arms extending from the terminals of the coils, anchor means preventing spreading of the coils, jaws having grooves in which said arms are fitted, plates secured to the jaws and extending across 45 the arms, and said anchor means being formed of wire.

ESPA S. GARDNER.
